UNITED STATES PATENT OFFICE.

CARL P. EICHLER, OF LAKewood, OHIO.

SAD-IRON HANDLE.

968,923.

Specification of Letters Patent. Patented Aug. 30, 1910.

Application filed June 25, 1909. Serial No. 504,212.

To all whom it may concern:

Be it known that I, CARL P. EICHLER, a citizen of the United States, and a resident of Lakewood, county of Cuyahoga, and State of Ohio, have invented a new and useful Improvement in Sad-Iron Handles, of which the following is a specification, the principle of the invention being herein explained and the best mode in which I have contemplated applying that principle, so as to distinguish it from other inventions.

A type of sad iron that has achieved very general popularity within recent years is characterized by the use of an interchangeable handle, one handle sufficing for the entire set of irons. While there has been a certain degree of similarity in the various types of interchangeable handle irons put on the market by different manufacturers, there have at the same time, been introduced certain divergencies, perhaps purposely, that render it difficult or even impossible to use with any particular iron, any handle other than the one designed to accompany it or a duplicate of the same. Chief among the differences thus found among the irons, which, obviously, must in their general characteristic be the same, is a varying width and cross sectional form in the transverse bar that is to be gripped by the gripping members of the handle. Since the latter then are made to engage with a particular width and form of transverse bar, the difficulty above noted arises, whenever it is attempted to use one make of handle with another make of iron.

The object of the present invention, is the provision of a handle that will be more or less universal in its adaptability for use with irons differing in the characteristics above referred to.

To the accomplishment of this and related objects, said invention, then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—Figure 1 is a side elevation of a sad iron and detachable handle therefor, such handle embodying my several improvements; Fig. 2 is a plan view of the same with a portion of the handle

broken away to reveal more clearly the operative parts thereof; Fig. 3 is a longitudinal vertical section through such operative parts of the handle, and top plate of the iron illustrating the parts in the position occupied when engaging the sad iron having a wide cross-bar; Fig. 4 similarly shows such parts in engagement with an iron having a narrower cross bar, or member to be gripped, than in the iron of Fig. 3; Fig. 5 illustrates several of such parts in disassembled condition; and Fig. 6 is a plan view of a broken detail.

In the type of sad iron under consideration, the body A of the iron is provided on its upper face with a plate *a* having a transverse bar *a'* which the interchangeable handle B is designed to securely grip when the iron is in use. By thereupon releasing such handle the latter may be transferred for use with another iron in the same manner. It is in the width and general form of such transverse bar that divergency is generally found in different makes of iron, and as stated, it is with a view to providing means whereby the handle may engage various forms of such bar with equal security, that the present handle has been devised. Such handle B then, comprises a base or plate *b* designed to be longitudinally seated on the upper face of the iron A and over such bar *a'*. The handle proper usually consists of a curved member of wood *b'* or other similar material that does not readily conduct heat. For the purpose of gripping the cross bar of the iron, base plate *b* is provided with a downwardly depending lug *b*² on its under face, that has an inclined face *b*³ adapted to engage one side of the bar or member to be gripped. Reciprocably held in the base so as to be movable at an acute angle to such inclined face *b*³ of the lug, is a plunger C which has its inner face *c* beveled for engagement with the other side of said bar. The angular relation of the plunger to the lug and the inclines of their respective faces are made such as to enable them to grip a bar with equal security, irrespective of the position of the plunger in its lower position; in other words, whether the bar be wide or narrow, such plunger if urged downwardly, will retain the same against the depending lug *b*². To thus actuate the plunger, I provide a handled lever C', one end *c'* of which is pivotally held in two ears *b*⁴ adjacent to the way *b*⁵, wherein plunger

C is held, a coil spring c^2 being located between such ears, and so engaging said lever as to urge the same, and thereby said plunger, downwardly.

5 Inasmuch as facility in assembling is a desideratum in all manufactured articles of this character, I have taken pains to so construct the several operative parts just described as to permit the completed device 10 to be put together manually, and that, too, with ease and expedition. With this object in view, the openings b^6 in ears b^4 provided for the reception of the inner end c' of the lever, are made of oblong form, so that said 15 lever may be introduced therethrough, and yet be locked in place when turned over into its normal substantially horizontal position by the terminal bend c^8 therein. The coil spring is in place when the end of the lever 20 is inserted into the ears; and before the lever is mounted in the ears its outer end is inserted through the upper end of the plunger. An extension of the coil spring is then snapped upon the body of the lever, 25 the end of such extension being recurved so as to form a hook for this purpose, as will appear from Figs. 2 and 3. Thereupon the parts, it will be seen are in complete operating engagement. It only remains then to 30 attach the handle c^5 , which may be conveniently made of wood, and threaded onto the outer end of the lever, as illustrated in Fig. 5.

Other modes of applying the principle of my invention may be employed instead of 35 the one explained, change being made as regards the mechanism herein disclosed, provided the means stated by any of the following claims or the equivalent of such 40 stated means be employed.

I therefore particularly point out and distinctly claim as my invention:—

1. In a device of the character described, the combination with a base formed with a 45 downwardly depending lug having a face inclined with respect to said base and adapted to engage one side of the member to be gripped; of a rectilinearly movable plunger reciprocably held in said base so as to be movable in a plane inclined oppositely to 50 the face of such lug, said plunger having its inner end beveled for engagement with the other side of said member.

2. In a device of the character described, the combination with a base formed with a downwardly depending lug having a face 55 inclined with respect to said base and adapted to engage one side of the member to be gripped; of a rectilinearly movable plunger reciprocably held in said base so as to be movable in a plane inclined oppositely to 60 the face of such lug, said plunger having its inner end beveled for engagement with the other side of said member; a handled lever adapted to actuate said plunger; and a spring connected with said plunger to move 65 the same toward said member.

3. In a device of the class described, the combination with a base formed with two transversely spaced ears on its upper face and with a downwardly depending lug on 70 its under face, said lug having an inclined face adapted to engage one side of the member to be gripped; of a plunger reciprocably held in said base adjacent to said ears so as to be movable at an angle to such inclined 75 face and adapted to engage the other side of said member; a handled member pivotally held at one end in said ears and adapted to actuate said plunger; and a coil spring located between said ears and connected with 80 said plunger to urge the same toward said member.

4. In a device of the class described, the combination with a base formed with two transversely spaced ears on its upper face 85 and with a downwardly depending lug on its under face, said lug having an inclined face adapted to engage one side of the member to be gripped; of a plunger reciprocably held in said base adjacent to said ears so as to be movable at an acute angle to such inclined 90 face and adapted to engage the other side of said member; a lever detachably mounted in said ears at one end and similarly engaging said plunger, intermediate of its ends; a handle for the free end of said lever; and a coil spring located between said ears and connected with said plunger to urge 95 the same toward said member.

Signed by me this 23. day of June, 1909. 100
CARL P. EICHLER.
